DESIGN FOR A TIRE

Kimball D. Smith, Akron, Ohio, assignor to The
B. F. Goodrich Company, New York, N. Y., a corporation of New York

Application August 18, 1937, Serial No. 71,165

Term of patent 14 years

To all whom it may concern:

Be it known that I, Kimball D. Smith, a citizen of the United States, residing at Akron, in the county of Summit and State of Ohio, have invented a new, original, and ornamental Design for a Tire, of which the following is a specification, reference being had to the accompanying drawing, forming a part thereof, of which;

Fig. 1 is a perspective view, partially in dotted lines, of a tire showing my new design.

Fig. 2 is a fragmentary plan view of the tire.

Fig. 3 is a section taken along the line 3—3 of Fig. 2, portions being illustrated in dotted lines.

I claim:

The ornamental design for a tire as shown.

KIMBALL D. SMITH.
